UNITED STATES PATENT OFFICE.

JAMES K. LANNING, OF FALL RIVER, MASSACHUSETTS.

SPINNING-RING.

SEARCHED AND COPY

1,392,067.

Specification of Letters Patent. Patented Sept. 27, 1921.

Application filed October 28, 1915. Serial No. 58,480.

To all whom it may concern:

Be it known that I, JAMES K. LANNING, a citizen of the United States, and a resident of Fall River, county of Bristol, and 5 State of Massachusetts, have invented an Improvement in Spinning-Rings, of which the following description, in connection with the accompanying drawings, is a specification, like characters on the drawings 10 representing like parts.

This invention relates to spinning rings and particularly to stationarily mounted spinning rings.

In order that the principle of the invention may be readily understood, I have represented an embodiment thereof in the accompanying drawing, wherein—

Figure 1 is a plan view of the preferred embodiment of my invention;

20 Fig. 2 is a vertical central section thereof upon an enlarged scale; and

Fig. 3 is a vertical section of a part of the ring.

An important object of my invention is 25 to provide a spinning ring of such construction as to result in a material reduction in the friction of the traveler thereon. Further objects of the invention will be set forth hereinafter. So far as I am aware, no successful spinning ring has been produced excepting by forging, which is machined down and then case-hardened and polished. The ring herein disclosed has said characteristics, and is therefore of true circular 30 form, a desideratum not secured through the use of sheet metal. The preferred form of traveler is one of mild steel, case hardened. Economical commercial production requires all travelers to be symmetrical in 35 form and double-ended, so that they may be placed upon the ring without any requirement that one end or the other be made the inner end. In accordance with the preferred embodiment of my invention, I have 40 provided rings peculiarly adapted to receive travelers of such double-ended formation, though my invention is not limited to the use of such a traveler.

In the figures, I have indicated the preferred embodiment of my invention.

Referring more particularly to Figs. 1 and 2, the basal portion of the ring is indicated at 2 and the upright body at 3, the traveler flange being generally indicated at 55 11. I have herein represented the inner edge 12 as blunt and of considerable vertical

extent and have shown the outer edge 13 as thin and as presenting substantially a single circumferential line. Preferably the top surface 14 of said flange is slightly 60 concave. At some suitable point between the inner and outer edges 12 and 13, and preferably at the point indicated, I provide an annular ridge 15 extending slightly above the top surface of said flange. Preferably 65 said ridge is positioned between the body 3 and the outer edge 13.

The function of the annular ridge 15 is to reduce the friction between the traveler and the body of the flange, or between foreign matter upon the traveler and said flange. In the irregular or up-and-down motion of the traveler heretofore referred to, contact is made by the traveler, not with the entire top surface of the traveler flange, 75 but with the annular ridge 15.

While within the broad scope and purpose of my invention, the said ridge 15 might be slightly interrupted at one or more points it is preferably continuous and of uniform 80 height throughout, thus insuring the least friction between it and the ring 16.

While I have herein represented the annular ridge 15 as provided upon a traveler flange having a thin outer edge, it is to be 85 clearly understood that my invention is not limited thereto, inasmuch as said ridge may be formed upon other types of traveler flanges, as, for example, those having a blunt outer edge, and inasmuch as in either case 90 the friction between the traveler flange and the ring is reduced by the employment of such ridge.

In the illustrated form of my invention I reduce the friction between the traveler 95 or foreign matter thereon and the traveler flange of the ring.

Having reference to that form of my invention shown in Figs. 1 and 2, it is my belief that the thin outer edge of the traveler 100 flange assists in a rapid dissipation of heat generated in the ring incident to the spinning operation. Moreover the provision of the thin outer edge permits the more ready application of the traveler thereto.

Obviously the lower flange of the ring may be of the same construction as the upper flange, thereby making the ring reversible.

In Fig. 3, I have shown in detail a part 110 of the ring. The top surface of the ring is provided with an annular ridge 18 hav-

ing the same function as the corresponding ridge shown in Fig. 2. The outer edge 19 of said traveler flange is preferably blunt. The inner edge 20 is also blunt.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A spinning ring provided with a traveler flange having its upper surface in the form of an annular trough, the upper limits of the inner and outer edges of said flange being in different horizontal planes and a friction reducing elevation between said inner and outer edges.
2. A spinning ring provided with a traveler flange, the upper surface whereof, between its inner and outer edges, is below the upper limit of said edges, whereby an annular trough or depression is provided, the upper limits of the inner and outer edges of said flange being in different horizontal planes and a friction reducing elevation between said inner and outer edges.
3. A spinning ring provided with a traveler flange having blunt inner and outer edges extending above the intermediate surface of the flange and also having a frictional reducing elevation between said inner and outer edges.
4. A spinning ring provided with a traveler flange having blunt inner and outer edges, the inner edge being of the greater vertical extent, the top surface of said flange between said edges being below the upper portions of said edges and also having a frictional reducing elevation between said inner and outer edges.
5. A spinning ring provided with a traveler flange having a substantially annular ridge upon its upper surface and constituting a friction reducing elevation between the inner and outer edges of said flange, said upper surface, excepting for said ridge, being below the upper limits of the edges of the traveler flange.
6. A spinning ring provided with an upstanding body and a traveler flange, the upper surface of the latter being recessed and also provided with a substantially annular ridge between said body and the outer edge of said flange.
7. A spinning ring provided with a trav-

eler flange having a concaved upper surface and also having elevated friction-reducing means upon said upper surface between the inner and the outer edges of the ring.

8. A spinning ring provided with a traveler flange having a dished upper surface and also having an elevated friction-reducing formation upon its upper surface between the inner and the outer edges of the ring.

9. A spinning ring provided with a traveler flange, the upper surface of which is concaved and is provided with an annular ridge spaced from the edges of the ring.

10. A spinning ring provided with a traveler flange, the upper surface whereof is concaved, said upper surface being provided with an annular ridge between the inner and the outer edges of the ring.

11. A spinning ring provided with a traveler flange having an annular concavity upon its upper surface between its inner and outer edges, and having an annular ridge upon said upper surface between the inner and outer edges of the ring, at least one of said edges extending at least as high as said ridge.

12. A spinning ring provided with a traveler flange having an annularly concaved upper surface between its inner and outer edges, said surface being provided with friction reducing means extending above the base of said concavity between the inner and outer edges of the ring, at least one of said edges extending at least as high as said friction reducing means.

13. A spinning ring provided with a traveler flange whose upper surface is annularly concaved, said upper surface being provided with an annular ridge whose top is below the level of at least one of the edges of the traveler flange.

14. A spinning ring provided with a traveler flange having an inner edge and a lower outer edge, the upper surface of said flange being annularly concaved, said upper surface having an annular ridge, the top whereof is below the top of the inner edge of said traveler flange.

In testimony whereof, I have signed my name to this specification, in the presence of two subscribing witnesses.

JAMES K. LANNING.
